TELEVISION REPRODUCING METHOD

Kurt Schlesinger, Berlin, Germany, assignor, by
mesne assignments, to Loewe Radio, Inc., a cor-
poration of New York

Application January 22, 1936, Serial No. 60,296
In Germany January 26, 1935

2 Claims. (Cl. 178—7.7)

In numerous instances in the television art it is necessary to convert rectangular image areas into trapezoidal image areas, for example in the case of all cathode ray tubes in which the image is projected on to an intercepting plate provided within the tube and disposed obliquely to the axis of the tube, and also in the case of transmitters operating with a spiral-aperture disc (Nipkow disc), the sectional area of which is always a trapezium bounded by two radii. It has already been shown in earlier application Ser. No. 46,126 in what manner this problem of the trapezoidal distortion may be accomplished by inclination of the plane of the object and the plane of the image when employing a lens of short focal distance. In the latter application, however, there has been described merely the accomplishment of the trapezoidal form. No mention was made on the other hand of the manner in which upon the distortion of the area a distortion of the scale occurs in the transverse or longitudinal direction.

The novel features which I believe to be characteristic for my invention are set forth with particularity in the appended claims. My invention, however, both as to its organization and method of operation together with further objects and advantages thereof may be best understood by reference to the following description taken in connection with the accompanying drawings, in which in Fig. 1 there is illustrated in what manner the error is occurring the disturbing effect of which shall be removed according to the present invention, Figs. 2a and 2b show the manner in which the recognitions take effect in the assembly of a television transmission system having a Nipkow disc. In Fig. 2a there is shown an arrangement with large scale error, while in Fig. 2b there is illustrated the optical arrangement according to the invention.

Fig. 3 shows the intercepting surface of an ikonoscope.

Fig. 1 shows a lens 1, which converts an object plane with the track 2 into an image plane with the track 3. All rectangular areas having vertical edges situated in the plane 2 appear in the image plane 3 with trapezoidal distortion. In the object plane the points $a-f$ are spaced equal distances apart. They correspond with the penetration points of the lines of a television image, which is situated vertically to the plane of the paper in the plane 2. Their reproduction points are to be found on the track of the image plane 3 by drawing the middle-point rays. They are designated $a'-f'$. It is to be recognised from the drawing 55 that the equidistant spacing of the object points

quite well corresponds with unequal spacing of the image points. In practice it is to be deduced from this that even line spacing in the object plane corresponds with uneven spacing in the image plane. This leads to strong distortions of the television image, and in numerous methods, for example in the repetition method for the purpose of avoiding flickering effect, even to incapability of performing the image transmission, as in the latter case the upper and lower halves of the image possess different scales and do not fit, therefore one against the other.

Closer investigation, however, shows that the described error in scale, which will be referred to in the following as "scale error," varies greatly in extent dependent on the angle at which the image-producing rays fall on the image plane 3. For example in Fig. 1 the same rectangular object area is disposed on one occasion between the points c, d, e, f (4) and on another occasion between the points a, b, c, d (5). In both cases there are derived from the rectangular areas 4 and 5 trapezoidal areas $4'$ and $5'$, which result between corresponding image points $c'-e'$ ($4'$) and $a'-c'$ ($5'$) respectively. In the case of $4-4'$ the centre of the image d of the original 4 develops laterally of the middle position d_0 of the image $4'$. The scale error in this case is very large. On the other hand in the case of $5-5'$ the middle of the reproduction level $a'-c'$ is met exactly at b' . The scale error, therefore, in this case is very small. It is to be recognised from this:

The smallest scale error is obtained in the case of a trapezoidal reproduction according to Fig. 1 in that range of position of object and image in which the image-producing rays, taken through the centre-point of the lens, impinge almost vertically on the image surface. Whereas in the case of normal reproducing optical systems the lenses are always so disposed that their plane is situated as far as possible vertically to the producing bundle of rays, as the aperture capable of being attained is then at a maximum, the lens in the case of a reproducing apparatus serving to produce trapezoidal distortions is so disposed in accordance with the invention that the rays fall obliquely thereon, whilst the image intercepting plane is situated vertically to the rays. The relative angles between the planes of the object, lens and image are not effected thereby, and also the degree of trapezoidal distortion governed by the angle in Fig. 1 remains practically invariable.

Fig. 2 shows the manner in which these recognitions take effect in the assembly of a television transmission system having a Nipkow disc. In

Fig. 2a there is shown an arrangement with large scale error. The lamp case 6 together with the film guiding rollers 7 and the lens 1 belongs to the casing 8 of the film projector, and in the arrangement according to Fig. 2a must, therefore, be disposed inclinedly to the foot 9 by means of a rotary joint 10. The middle-point ray 12 meets the Nipkow disc 11, which replaces the image plane 3 in Fig. 1, at an inclined angle, and the lens 1 at right-angles. This arrangement, despite good control of the intensity of the light due to the favourable position of the lens 1, is incapable of use for television purposes because the decomposition of the lines is accompanied by a considerable scale error.

The optical arrangement according to the invention is illustrated in Fig. 2b. The same differs from Fig. 2a by the fact that this time the middle-point ray 12 impinges on the image plane, i. e., the disc 11, vertically. The lens 1 and the film 7 must accordingly be inclinedly disposed in relation to this middle-point ray, whereby the differences in direction between the optical planes 7, 1 and 11 do not vary in relation to Fig. 2a. This arrangement operates practically without scale error, and offers from the point of view of operation the advantages that (1) the adjustment of the trapezoidal distortion may take place by different inclination of the planes of film and lens, i. e., small and readily manipulated structures, whereas in Fig. 2a this can only be adjusted by inclination of the entire machine casing, and that (2) the machine 8 and lamp case 6 may remain in horizontal disposal.

It must be specifically remarked that the image-producing rays shown in the drawings, for example the middle-point rays, are in no way identical with the rays which do in point of fact cause the technical reproduction. The requirements laid down in the application as regards the disposal of the constructional rays of the geometric reproduction are fulfilled by correct mutual adjustment of film lens and plane of the image. Independently thereof the bundle of rays proceeding from the lamp 6 may now be disposed in space as desired. In practice this bundle with certainty only be disposed in such fashion that there is obtained the largest possible lighting current through the entire system up to the Nipkow disc. In practice this optimum guiding

of the lighting rays certainly coincides in the majority of cases as regards their direction with the middle-point ray of the reproducing construction in the manner illustrated diagrammatically in Figs. 2a and 2b.

In Fig. 3 the intercepting surface of an ikonoscope is designated 13, whereby the problem exists of reproducing optically without scale error the trapezium 14, which is projected thereon by a cathode ray with constant deflecting potential. According to the invention, the middle-point of the lens must be disposed on the perpendicular line 12 provided at the centre of the intercepting plate 13, and an adjustable inclination in relation to this axis 12 imparted to the lens 1 and to a matt plate 15. On to the matt plate 15, which may also be a mirror or a tangible air image, there is projected in the manner known per se by means of a reproducing lens 16 an image of the remote object. 15 and 16 may also be related parts of a reproducing camera.

I claim:

1. In a television system, means to produce a planar optical image, a planar light responsive image receiving area angularly positioned relative to the plane of the optical image, means for scanning the image in the plane of the image receiving area, and an optical means for focussing the optical image upon the image receiving area, said optical means having its main axis so located relative to the image receiving area that the light ray from the central area of the planar optical area impinges upon the image receiving area in a substantially normal direction thereto and so that a normal to the optical axis is substantially in the plane of the bisector of the angle between the planar optical image and the image receiving area, whereby a substantially rectangular optical image is converted into a substantially trapezoidal image on the image receiving area and the variance in length of the shorter and longer parallel sides of the trapezoid so formed are proportional to variances in length in the scanning pattern at the plane of the image receiving area.

2. The system claimed in claim 1 wherein the planar light responsive image receiving area comprises a mosaic electrode structure supported within a cathode ray tube and wherein the scanning means comprises an electron beam.

KURT SCHLESINGER. 50
